M. H. SLATER

SMOKING DOLL

Filed Nov. 3, 1921

FIG. 1.

FIG. 2.

Inventor:

Mabel H. Slater,
By her attorney, Charles S. Gooding.

Patented Nov. 20, 1923.

1,475,034

UNITED STATES PATENT OFFICE.

MABEL H. SLATER, OF NEW YORK, N. Y.

SMOKING DOLL.

Application filed November 3, 1921. Serial No. 512,591.

To all whom it may concern:

Be it known that I, MABEL H. SLATER, a citizen of the United States, residing at New York, in the county of New York and State of New York, have invented new and useful Improvements in Smoking Dolls, of which the following is a specification.

This invention relates to a toy consisting of a smoking doll.

10 The object of the invention is to provide a doll, statuette or idol which may be caused to emit smoke from the eyes, nose or mouth and which also may be utilized to form a holder for pill shaped particles known as 15 devil's eggs which, when lighted, will expand and form horns or curls, thus providing an attractive and amusing article which, when not in use as a smoking doll, may be used as an ornamental piece of bric-a-brac 20 or as a paper weight.

To these ends the invention consists in a smoking doll constructed as hereinafter described and particularly as pointed out in the claim.

25 Referring to the drawings:

Figure 1 is a perspective view of my smoking doll.

Fig. 2 is a vertical, sectional elevation of the same.

30 Like numerals refer to like parts in the views of the drawings.

In the drawings, 5 is a head provided with eyes 6, nose 7, mouth 8 and neck 9. The neck 9 is substantially cylindrical and fits in 35 a cylindrical recess 10 formed in a base 11. The base and the head are formed of non-inflammable material. Passages or openings 12 extend from the interior of the head through the eyes to the outside thereof. A

passage 13 extends through the nose and a 40 passage 14 extends through the mouth. An inlet passage 15 extends from the outside of the base to the top thereof at a point inside the head. A piece of inflammable material 16, such as tobacco incense is 45 placed upon the base 11. It is then lighted and the head 5 is inserted in the recess 10. Smoke will issue through the eyes, nose and 50 mouth, the air for combustion entering the head through the inlet passage 15. In the top of the head recesses 17 are provided and in these recesses are placed pellets 18 known as devil's eggs. These pellets upon being lighted will burn and expand forming curls or horns 19.

55 I claim:

A smoking doll having, in combination, a hollow head provided with openings through the eyes, nose or mouth and a cylindrical neck portion, a base upon which said head is mounted, said base being provided in the top thereof with a cylindrical recess adapted to receive said neck portion and also to receive an inflammable material, and position the same within said cylindrical recess, said base being also provided with an inlet passage extending from the outside thereof into said recess, whereby upon lighting said material smoke may be caused to issue from 60 said nose, eyes or mouth.

65 In testimony whereof I have hereunto set my hand in presence of two subscribing witnesses.

70 MABEL H. SLATER.

Witnesses:

A. A. FONES,
F. W. M. HELLER.
